CESARE SONCINI, OF BRESCIA, ITALY, ASSIGNEE TO SOCIETÀ ITALIANA ERNESTO BREDA PER COSTRUZIONI MECCANICHE, OF MILAN, ITALY

AUTOMATIC FIREARM HAVING A RECOILING BARREL AND AN AMPLIFYING PUSH LEVER

Application filed February 24, 1928, Serial No. 256,678, and in Italy March 5, 1927.

Automatic firearms with recoiling barrel are known in which the bolt is moved rearwardly by means of an accelerator lever. Known weapons of this kind exhibit a certain 5 lack of coordination between the various operating parts, which is a disadvantage from the point of view of reliable operation.

Furthermore, the parts of the known weapons have not the form which is best 10 adapted to insure that degree of reliability and simplicity which is desirable.

The principal object of the present invention is to obtain a perfect cooperation between all the various parts, the construction 15 being simple, the operation reliable and the control easy.

The improved weapon is characterized in that the accelerator lever and the bolt are formed and arranged so that the one operates 20 upon the other without the intermediary of any spring and without contact between the two being broken at any time when the weapon is in use, and in such a manner that the aforesaid lever drives and controls the 25 movements of the breech and the bolt directly and all the other operating parts indirectly.

The weapon is further characterized by the construction and arrangement of the various 30 parts which have been adopted with a view to obtaining the above-mentioned desirable characteristics, as well as by certain specific inherent and functional qualities of each part.

In the accompanying drawings, one embodiment of the invention is illustrated by way of example, a weapon particularly adapted for use in arming aircraft being shown in which belt-feed is employed.

It will be understood, however, that the weapon may be modified, and that other arrangements than belt-feed may be used. Consequently, while some of the components described below are essential characteristics of 45 the invention, others are variable in accordance with the nature of the weapon under consideration.

In the accompanying drawings, the various parts of the weapon are shown drawn 50 to various scales, but in all the figures the

same reference numerals relate to the same parts.

In the drawings:

Figure 1 is a longitudinal section of the 55 weapon;

Fig. 2 is a cross-section through the bolt on line 2—2, Fig. 1;

Figs. 3 and 4 show in section and in plan, respectively, the means for feeding the belt;

Figs. 5 and 6 show two positions, engaged 60 and disengaged, of the locking member for the bolt;

Figs. 7 and 8 are perspective views of the 65 said locking member and the guide plate with which it cooperates;

Figs. 9, 10 and 11 show, respectively, the accelerator lever in two different positions in section, and in perspective;

Fig. 12 represents the trigger mechanism;

Figs. 13 and 14 show, in perspective and 70 in section, the means for taking cartridges from the belt and transferring them to the firing chamber.

With a view to facilitate an understanding of the following description, a comprehensive list of the component parts of the 75 weapon is given.

In the drawings, 1 indicates the breech casing, 2 the barrel, 3 the feed conduit, and 80 4 a cover for the casing. 5 is a lever for moving the belt, 6 a wing on lever 5, 7 is the bolt, and 8 the breech end or extension of the barrel. 9 is a vertically-reciprocating member for transferring the cartridges. 10 is a cam

groove formed in the casing to control transfer member 9, 11 is the firing pin, 12 the main recoil spring, and 13 a damping spring. 14 85 is the accelerator lever which moves the bolt 7, and 15 is a carriage attached to extension 8 and with which the lever 14 is connected.

16 is a device for regulating the tension of spring 12, 17 a locking member, and 18 is a slotted guide controlling locking member 17.

19 (Fig. 12) is the trigger casing, 20 a downward extension of the breech casing through which the empty cartridge shells are ejected and 21 is a rearward extension of the breech 90 casing. 22 is a guide rod for the recoil spring 12, 23 (Fig. 13) a double claw or gripper which holds the cartridges during their

95

100

movement from the belt to the firing chamber, 24 a claw movably mounted on the transfer member 9, and 25 is a tooth on the transfer member which guides the said member 9 by engagement with cam 10. 26 (Figs. 13 and 14) is a holding member for the cartridges, 27 (Fig. 12) the hammer for the firing pin 11, 28 a detent for the hammer, 29 the trigger control lever, 30 a plunger operating the hammer, 31 a detent for insuring synchronization when the weapon is required for use on aircraft and firing is to take place through the propeller, and 32 is a plunger for controlling the operation of detent 31.

15 The accelerator lever 14, shown in detail in Figs. 9, 10 and 11, is given a form which renders it particularly adapted to fulfill the purpose for which it is required. It comprises two angularly-arranged arms, as will be readily seen from the drawings, the upper arm being slightly bent and its end making contact above with a flat 37 formed on the bolt. As the abutting part 38 of the carriage 15 engages a point between the end of the 25 upper arm and the pivot of the accelerator lever, it effects a movement with an increasing acceleration according as its said point of engagement approaches towards the pivot of the lever. The lower arm of the lever carries at its end a roller 36 which rolls, during the rotary movement of the lever, on the arc formed by the surfaces of the two spaced parts 39 of the carriage, and it remains constantly in contact therewith.

35 The characteristic of this device, which moves the bolt without the intermediary of springs, resides in the arrangement which permits it to operate as a true control for all the movements taking place in the mechanism 0 of the weapon, since the two parts 36 and 39, by reason of their form, remain always in contact with one another when the weapon is in use, so that the barrel extension 8, as well as the bolt and, also, indirectly, all the other 5 components, operate under the control of the lever device. When the bolt recoils independently of the barrel extension, the position of the upper arm of the lever is determined by the flat 37 on the bolt, while the 0 lower arm determines the position of the carriage 15 and fixes it at its upper part, as shown in Fig. 9. Consequently, it determines in a precise manner the position of the barrel extension 8 to which the carriage is in turn 5 connected. Fig. 10 shows the position of the accelerator lever when the mechanism is in closed position. In this position, the carriage 15 moves with the extension 8, while the accelerator lever is pivoting about pivot 35 0 rigid with the breech casing.

The closing means for the weapon is of a form adapted to cooperate with the above-described arrangements, and its characteristics are such as to permit the feeding of the 5 weapon by means of a belt from above in the

manner yet to be described. The closing device is of the known type, embodying a lock, but it is distinguished not only by its special structure but also by the fact that it is disposed at the head and to one side of the bolt and not beneath it, in the bottom of or towards the middle of the bolt, as in known arrangements.

The arrangement at the head of the bolt has the advantage that vibration during 75 firing is eliminated, and the arrangement to one side enables the vertical passage for the cartridges to be kept free, which is of great importance in the case of weapons used on aircraft. The closing arrangement essentially comprises a locking member 17 having a laterally-projecting rhomboidal extension or stud 34 which engages in a slot or groove formed in the closure plate 18 which guides it (Figs. 5-8).

80 The trigger mechanism is contained within in a casing or receptacle 19 external of the weapon, as shown in Fig. 2 and in Fig. 12. It comprises the previously-mentioned hammer 27, which is cocked by the bolt during 90 its recoiling movement and is held cocked by the detent 28. In the position shown, the hammer is engaged by said detent.

When the bolt is returned to closing position, it contacts, through a tooth, with the 95 lower extremity 42' of the trigger lever 29. This lever is moved forward; and, in consequence, the upper end 43 of the detent 28 is pushed forward, thereby releasing the hammer. The latter moves to strike against the 100 firing pin 11 under the impulse of the spring-operated plunger 30.

In a weapon which is required to fire in synchronization with the movement of a motor, as is necessary in the case of weapons used 105 on aircraft, it is not sufficient that the hammer be free to move when the weapon is closed; it is also necessary that the movement of the hammer shall take place in phase with the rotation of the propeller and, consequently, of the motor. For this purpose the synchronizing pawl 31 is provided which, with its tooth 45, forms a device controlling the operation of the hammer so that the actuation of the latter is only possible when the synchronizing pawl is displaced by the motor through a spindle 44 (Fig. 2) sufficiently to free the hammer. This movement of the synchronizing pawl may be effected by means of any of the arrangements already known in 115 connection with weapons of a like kind.

The power of the recoil spring 13 may be varied by means of the regulating screw 16 (Fig. 1) which is rotatable within the extension 21 of the breech casing, and the power 125 of the spring is determined according to the position of the screw. This adjustment device is of particular utility in the case of machine guns employed on aircraft.

130 The devices used in the present weapon

are designed for use with bolt-loaders and, consequently, they are adapted to carry out the usual three required steps with the cartridges, that is to say, they cause them to leave the belt, move towards the firing chamber and finally enter the latter.

These devices, however, possess certain characteristic features which are designed to provide satisfactory cooperation with the other special components and an efficient performance of their own particular functions.

It is to be observed that the feed of the cartridges is effected by the mechanism which also controls the movement of the belt. The transfer of cartridges from the belt to the firing chamber is effected in the following manner:

Into the feed passage 3, which is of ordinary form, the cartridges are fed by a belt (not shown) of fabric or metal which may be flexible or not and which passes the cartridges into a position where the jaws of the gripper 23 engage over the rim of the cartridge as the bolt 7 moves forward. On firing, the bolt moves rearward (to the left in Fig. 1) and the cartridge, which is then engaged by the gripper, as just stated, is thus withdrawn from the belt.

As the cartridge becomes completely freed from the belt, the boss or tooth 25, owing to the shape given the cam groove 10 with which it is engaged, causes the transfer member 9 to move downward, thereby pushing the cartridge downward from between the jaws of gripper 23 into a position in which its rim engages between guides 33 on the bolt and rests against the end of the pivoted holding member 26. When this position is reached, the rearward movement of the bolt is completed and its return movement commences, during which time the cartridge is pushed into the firing chamber.

Before the return or closing movement of bolt 7 is completed, the transfer member or carrier 9 is returned by the cam groove 10 to its raised position, and the gripper 23 is ready to grasp the next cartridge in the belt. When the recoil movement of the bolt commences, the spent cartridge is withdrawn from the firing chamber by the engagement of guides 33 with the rim of the cartridge; and after withdrawal of the said spent cartridge, the latter is ejected through opening 20 (Fig. 2) by being pushed past the end of the holding member or stop 26 by the lower end of the previously-mentioned claw 24 which is pivotally mounted on carrier 9 (Fig. 3). The holding member or stop 26 is itself yieldably mounted, as shown in Fig. 4.

The weapon also possesses certain important distinguishing characteristics in connection with the feed of the belt. In known types of belt-driven machine guns, the operation is effected by means of a simple lever pivoted at any convenient point upon the

breech casing and operating upon a part of the feeding carriage of the belt, the other end of the lever being guided by a cam provided on the bolt.

This arrangement works satisfactorily only when the distance between lever and bolt is reduced to a minimum, so that the imposition of considerable strains upon the lever is avoided.

In the present case, the breech end or extension 8 of the barrel and the breech casing 1 have been given a cylindrical form to facilitate accurate and easy manufacture; but this, while being of great importance from the point of view of production and operation, has the effect of increasing the distance of the feed lever 5 from the bolt and, in consequence, its pivot 40 becomes of such excessive length as to affect the operation disadvantageously. To overcome this objection, a device is provided in which the lever 5 is associated with a wing 6 which is capable of oscillating about a long pivot 41 fixed in the breech casing, under the control of a tooth 42, which engages in a cam groove (not shown) formed in the bolt. This oscillating wing 6 transmits movements to lever 5 without strain.

Summarizing, it is clear that from the point of view of operation, the improved weapon possesses important advantages. It is provided with a locking device arranged at one side and at the head of the bolt where it cannot impede the feed of the cartridges from above, and their ejection from below; it also possesses a feed-lever system which permits the adoption of a cylindrical form for the barrel extension and the breech casing, this lever being combined with a movement-transmitting wing; and it is furnished with a U-shaped gripper which moves the cartridges from the belt and grips them symmetrically and centrally of their two sides. Finally, a carrier moving in a straight path is provided to transfer the cartridges in a satisfactory manner.

All these parts or devices operate under the control of means which include an accelerator lever and a carriage cooperating and in constant connection therewith. Furthermore, the trigger device comprises not only a safety detent operating according as the weapon is closed, but also a synchronizing detent operating in accordance with the movement of an outside motor that, for example, drives the propeller of an aircraft.

What I claim is:

1. In a machine gun, a breech casing; a recoiling barrel; a sliding bolt having a flat on its under face; a carriage fixed to the breech end of the barrel; and an accelerator lever embodying two angularly-arranged arms mounted at the apex of the angle to rock about a pivot fixed to said casing, one arm projecting upwardly into the path of the carriage

for coaction therewith and with said flat, and the other arm projecting toward said carriage and having a constant sliding engagement with the same.

5. 2. A machine gun, according to claim 1, in which the carriage is provided with an abutment adapted to strike against the upwardly projecting arm of the accelerator lever between the pivot of the lever and the free end 10 of said arm.

3. In a machine gun, a breech casing; a recoiling barrel; a sliding bolt having a flat on its under face; a carriage fixed to the breech end of the barrel and embodying two spaced 15 depending members having their front edges curved forwardly; and an accelerator lever embodying two angularly-disposed arms mounted at the apex of the angle to rock about a pivot fixed to said casing, one arm projecting

20 upwardly into the path of the carriage for coaction therewith and with said flat, and the other arm projecting through the space between the depending carriage members and terminating in a roller which has a constant 25 sliding engagement with the curved edges of said members.

4. A machine gun, according to claim 3, in which the carriage is provided with an abutment adapted to strike against the upwardly 30 projecting arm of the accelerator lever between the pivot of the lever and the free end of said arm.

5. A trigger mechanism for machine guns, comprising a trigger lever provided with a 35 circular recess; a hammer cocked by the bolt of the gun; a spring-actuated plunger for operating the hammer; and a pivoted detent for holding the hammer in cocked position having one end constantly engaged in said 40 recess and the other end releasably engaged with the hammer, said trigger lever being rocked by the closing movement of the bolt and thereby rocking the detent about its pivot so as to disengage the hammer.

45. 6. A trigger mechanism for aircraft machine guns, comprising a trigger lever provided with a recess; a hammer cocked by the recoil movement of the bolt of the gun; a spring-actuated plunger for operating the 50 hammer; a pivoted detent for holding the hammer in cocked position having one end engaged in said recess and the other end engaged with the hammer, said trigger lever being rocked by the closing movement of the 55 bolt and thereby rocking the detent about its pivot so as to disengage the hammer; a spindle to be driven from the motor of the aircraft; and a synchronizing detent on said spindle for controlling the operation of the 60 hammer in phase with the rotation of the propeller of the aircraft.

7. In a machine gun of the belt-feed type, a breech casing; a recoiling barrel; a sliding bolt; a gripper for removing the cartridges from the belt during recoil provided 65

with a pair of claws for engaging the cartridges on both sides; a reciprocating block for transferring the cartridges from the gripper into position to be moved into the firing chamber by the bolt, and a spring- 70 operated lever mounted on the side of the bolt to hold the cartridges in position preparatory to their entry into the firing chamber.

8. In automatic firearms, a recoiling bar- 75 rcl; a sliding bolt; and an accelerator device comprising two relatively-moving parts, one embodying a member having a shaped surface and connected to the breech end of the barrel, and the other embodying a two-armed 80 lever mounted to rock about a fixed pivot, one arm being in contact with the bolt, and the other arm in permanent sliding contact with the shaped surface of said member.

9. An automatic firearm, according to 85 claim 8, additionally provided with a locking member arranged at the head and to one side of the bolt and connected to the same, a closure plate provided with a guide slot, and a stud on the locking member slidably engaged 90 in said slot and whereby said member is controlled.

10. In a machine gun of the belt-feed type, a breech casing; a recoiling barrel; a sliding bolt having a cam groove in its upper face; a 95 rocking, pivotally-mounted feed lever for moving the belt step by step and operated indirectly by the bolt during its reciprocating movement; and a transmission connection between the bolt and the feed lever for effecting such indirect operation of said lever; such connection embodying an oscillating wing, and a vertical pivot on the breech casing and about which the wing swings, said wing having a recess to receive the pivot of the feed lever and also having a pin that projects into the cam groove in the bolt.

11. In a machine gun of the belt-feed type, a breech casing; a recoiling barrel; a sliding bolt; a gripper carried by the bolt for removing the cartridges from the belt during recoil, said gripper being arranged in a plane parallel with the axis of the bolt and having claws at its ends for engaging the cartridges on both sides; a reciprocating block for transferring the cartridges from the gripper into position to be moved into the firing chamber by the bolt; and a screen-operated lever mounted in the side of the bolt to hold the cartridges in position preparatory to their entry into the firing chamber.

12. In a machine gun of the belt-feed type, a breech casing provided with a cam; a recoiling barrel; a sliding bolt; a gripper carried by the bolt for removing the cartridges from the belt during recoil; a reciprocating block for transferring the cartridges from the gripper into a position to be moved into the firing chamber by the bolt, said block 125 130

slidable in rectilinear grooves formed in the bolt in a direction normal to its axis; and a tooth on the block engaged with the cam on the breech casing to control the movements of
5 the block.

In testimony whereof I affix my signature.

CESARE SONCINI.
